UNITED STATES PATENT OFFICE

SAMUEL S. COLT, OF ORANGE, NEW JERSEY

CONCRETE-FORM-CLAMPING DEVICE

Application filed May 29, 1928. Serial No. 281,413.

This invention relates to adjustable clamping devices for retaining the walls of concrete pouring forms in desired assembled relation; and the present invention has reference, more particularly, to further improvements in the general type and kind of clamping devices shown in my copending application for Letters Patent of the United States, Ser. No. 266,995, filed April 3rd, 1928.

10 The present invention has for its principal object to provide in combination with adjustable clamping devices novel construction and arrangement of cooperative tightening wedges together with a novel means for locking said wedges in adjusted set-up positions relative to the said clamping devices. The invention also has for an object to provide an associated relation of clamp-bar tightening wedge so arranged that the latter 15 is retained in assembled relation to the former and yet free for operative movement relative thereto.

20 Other objects of the present invention, not at this time more particularly enumerated, will be clearly understood from the following detailed description of the same.

The present invention is illustrated in the accompanying drawings, in which:—

Figure 1 is a plan view of one arrangement and construction of the novel adjustable clamping devices of this invention operatively related to assembled form walls, the latter being shown in horizontal section; Fig. 2 is a side elevation of the structure as arranged and shown in Fig. 1; Figure 3 is a fragmentary vertical section, taken on line 3—3 in Fig. 1, but drawn on an enlarged scale; Fig. 4 is a horizontal section, taken on line 4—4 in Fig. 3; and Fig. 5 is another horizontal section, taken on line 5—5 in Fig. 3.

Fig. 6 is a fragmentary plan view, showing a modified arrangement and construction of the adjustable clamping devices embodying the principles of this invention; and Fig. 7 is a vertical section through the same, taken on line 7—7 in Fig. 6.

Similar characters of reference are employed in the above described views, to indicate corresponding parts.

Referring to Figs. 1 to 5 inclusive, the reference character 10 indicates the form walls so arranged as to provide a mold or form of rectangular cross-section, such as would be employed in pouring concrete piers, 55 columns and similar structures.

The clamping devices for retaining the form walls 10 in operative assembled relation comprises, according to the present invention, a set of four mutually interengaging clamping bars 11. Each clamping bar comprises a stretcher or bar made of flat steel or other suitable material. Connected with one end portion of each stretcher or bar 11, and in overlying parallel relation thereto 60 is a clip block 12 cut-away at its underside to provide a transverse opening or passage 13 bounded at one or the outer side thereof by an abutment member 14 having a footing on the face of the stretcher or bar 11 and at 65 the other or inner side thereof by a spacing boss 15 also having a footing on the face of the stretcher or bar 11. Said clip block is rigidly secured to the stretcher or bar 11 by rivets 16 extending through the abutment member 14 and underlying portion of the stretcher or bar, and also by a rivet 17 extending through the spacing boss 15 and the portion of said stretcher or bar which underlies the same. The spacing boss 15 may be 70 omitted if desired leaving the end of the passage or slot 13 open. It will be obvious that other means of fastening said clip block and stretcher or bar together may be utilized, the above described means being merely illustrative on one practical arrangement in this 75 respect.

In assembling the stretchers or bars 11 together around the form walls 10, the free end of one such stretcher or bar is passed through 80 the opening or passage 13 beneath the clip block 12 of an adjacent stretcher or bar, in the manner clearly indicated in the accompanying drawings. Assembled with each stretcher or bar 11, so as to be transversely 85 movable through the opening or passage 13, in a position intermediate the abutment member 14 and the assembled end portion of an adjacent stretcher or bar, is a tightening wedge 18 having an oblique or inclined 90 95 100

margin 19 at its outer side. The inner face of the abutment member 14 is also formed to provide an oblique meeting face 20 corresponding to the oblique side 19 of the wedge, and against which the latter thrusts when actuated. It is also of advantage to laterally chamfer the oblique or inclined margin 19 of said wedge in a downward and outward direction from its top face and to correspondingly chamfer the oblique meeting face 20 of the abutment member 14, such construction tending to maintain the wedge flat on a surface of the stretcher or bar 11 when actuating the same in service. In order to retain the wedge in non-separable and yet operative relation to the stretcher or bar with which it is associated, I provide in the upper face of the wedge body a countersunk cavity which provides keeper shoulders 21 operative in the manner subsequently explained.

The means for locking the wedge 18 in any desired operative position to which it has been moved in service comprises, in one form, the following devices:

Mounted on the outer end portion of the clip-block 12 is a gripper piece 22, having at one end a downwardly projecting fulcrum shoulder 23, and adjacent its other end having a downwardly extending gripping member or stud 24. Said clip-block 12 is provided, above the path of movement of said wedge 18 thereunder, with an opening or slot 25 through which said gripping member or stud 24 extends, whereby the free extremity of the latter may be caused to bear bitingly on the upper surface of said wedge 18 and within the boundaries of the keeper shoulders 21 thereof. Said gripping member or stud 24 may be provided, adjacent its free end, with a laterally projecting tongue or lug 26, which, when the parts are assembled together, will extend under the marginal portion of the opening or slot 25 to thereby prevent accidental upward displacement of the gripper piece 22 and its gripping member or stud 24. Extending upwardly through the assembled stretcher or bar 11 and attached clip-block 12 is a connecting bolt 27, the squared head of which is preferably countersunk somewhat in the body of the stretcher or bar to hold the same against turning. The rear end of said gripper piece 22 is bifurcated, as at 28, to permit the free threaded end of said bolt 27 to pass upwardly therethrough. Arranged on said threaded end of said bolt 27 is a wing-nut 29 which may be tightened down on the gripper piece 22. If desired a cross-pin 30 may be passed through the free end portion of the bolt 27 above the wing-nut 29 to limit the loosening movement thereof, so that while it may be manipulated to loosen or tighten the gripper piece and its gripping member or stud 24 relative to the wedge 18, yet the parts cannot become accidentally disassembled or lost. Since the gripping mem-

ber or stud 24 enters the cavity of the wedge 18, bounded by the keeper shoulders 21, and is maintained in such position even when the gripper piece is loosened, it follows that the wedge under the latter condition is free to move and yet cannot be accidentally lost since the shoulders 21 will stop the wedge at some point before it can escape the opening or passage of the clip-block 12.

Furthermore, the arrangement of the wedge, thus retained in operative assembled relation to the clamping devices is such that, when the latter are not in use, the wedges may be turned or folded into the opening or passage 13, and then locked in such arrangement, so that the stretchers or bars may be compactly bundled together for storage or for carriage from place to place.

When operatively assembling the clamping devices in encircling and holding relation to angularly disposed form walls 10, the series of stretchers or bars 11 are arranged at right angles one to the other against the outer faces of the latter, with the free end of one stretcher or bar engaged through the opening or passage 13 of the clip-block 12 of the next adjoining stretcher or bar, and so as to lie intermediate the abutting form wall and the wedge 18 of the latter stretcher or bar, the wedges being initially withdrawn to loosened relation. When the parts are thus assembled relative to the form to be clamped thereby, holding pins, preferably in the form of split cotter pins 31, are inserted through a selected opening or perforation 32 of a longitudinal row thereof provided in the free ends of the stretchers or bars 11, whereby said pins are located at the outer sides of adjacent interengaged stretchers or bars to thereby prevent disassembling of the thus interconnected clamping devices. When the parts are thus disposed, the clamping devices are ready to be finally tightened up and locked in close gripping relation to the form walls. The latter operation is attained by driving home the wedges 18, thus taking up all slack in the form encircling clamping devices, and thereby securing a snug and tight gripping and embracing relation of the latter to the form. After the wedges 18 are thus driven home to operative tightening position, the previously loosened wing-nuts 29 are screwed down on the bolts 27, thus pressing down on the gripper pieces 22, as fulcrumed on their shoulders 23, and thereby thrusting downwardly the gripping members 24 into biting and holding engagement with the wedges, all whereby said adjusted and tightened wedges are firmly gripped and held against back-slipping or displacement from their operative thrusting relation to the associated stretcher or bar 11, and thus securely retaining the clamping devices against accidental displacement from operative form clamping positions.

Attention may here be called to a convenient means provided in connection with the clip-block 12 from holding the cotter pins 31, when not in use, and also for spreading said pins when it is desired so to do. For these purposes, the outer end of the clip block is provided with a cavity 33 bounded at its upper side by a chamfered or chisel edged wall 34, and through this end of the clip-block extend transverse openings 35. The openings 35 serve to receive and hold a cotter pin 31, when the same is not in use, thus assuring its presence when needed (as shown in Figs. 3 and 4); the chisel edged wall 34 may be utilized to engage between and spread the arms of the pin 31 to allow for outward spreading tension thereof when used (this being shown by dotted lines in Fig. 3).

From the above description it will be obvious that the wedges 18 may be adjusted to a nice degree of tightness, and that when so adjusted the gripping members may be caused to quickly engage and securely hold the same in the positions to which they have been adjustably tightened.

Referring now to Figs. 6 and 7, I have shown therein a somewhat modified arrangement and construction of wedge locking means, which embodies, however, the principles of this invention. In this construction I omit the separate rigidly securing rivets 16 from the outer end of the clip block 12, and also omit the separable gripper piece 22, substituting for the latter a set-screw 36 mounted in the wall of the clip block 12 so as to project downwardly into the underlying opening or passage 13 into engagement with the wedge 18. A jamb nut 37 may be utilized to lock the set-screw in desired position. As shown in Figs. 6 and 7 a bolt 38 is extended through the outer end of the clip-block and through the underlying stretcher or bar 11, its threaded end being supplied with a wing-nut 39. When the wedge 18 has been adjusted to tightened position the wing-nut 39 is manipulated to draw down the clip-block thus carrying the set-screw 36 into biting and holding relation to the wedge. It will also be understood, that the clip block 12 may be rigidly secured to the stretcher or bar 11, and the set screw alone manipulated to tightened or loosened position, to lock or free the wedge 18 as desired.

I am aware that changes, other than those above mentioned, may be made in the above-described clamping devices, as well as in the details of the construction of the same, without departing from the scope of this invention as described in the foregoing specification, and as defined in the appended claims. Hence, I do not limit my present invention to the exact arrangements and combinations of the devices and parts as set forth in the foregoing specification, nor do I confine myself to the exact details of the construction

of said parts as illustrated in the accompanying drawings.

I claim:

1. In a form clamping device, a clamp bar structure having means at one end to mount a tightening wedge for operative movement relative thereto and means to receive the end of a cooperating clamp bar to dispose the same between said wedge and the form to which the clamping device is applied, said wedge mounting means having a releasable gripping means engageable with said wedge to lock the same in desired operative position, and said wedge having a depressed portion in a face thereof bounded by keeper shoulders adapted to cooperate with said gripping means when the latter is loosened to thereby retain said wedge in assembled relation to said clamp bar structure. 70

2. A form clamping device, comprising 85 mutually interengageable clamp bar structures adapted to be mounted in encircling relation to a form to be held thereby, each clamp bar structure having at one end a passage forming means provided with a wedge thrust abutment, a tighten-wedge movable endwise through said passage forming means and against said thrust abutment, said passage forming means of one clamp bar structure being adapted to receive a portion of an adjacent clamp bar structure for disposition between said wedge and the form to which the clamping device is applied, and a releasable gripping means carried by each clamp bar structure and passage forming means, 90 said gripping means being engageable with said wedge to lock the same in desired operative position. 95

3. A form clamping device as characterized in claim 2, in which said wedge is provided with a laterally beveled edge and said thrust abutment is provided with an undercut beveled edge to cooperate therewith. 105

4. A form clamping device, comprising 110 mutually interengageable clamp bar structures adapted to be mounted in encircling relation to a form to be held thereby, each clamp bar structure having at one end a passage forming means provided with a wedge thrust abutment, a tighten-wedge movable endwise through said passage forming means and against said thrust abutment, said passage forming means of one clamp bar structure being adapted to receive a portion of an adjacent clamp bar structure for 115 disposition between said wedge and the form to which the clamping device is applied, a releasable gripping means carried by each clamp bar structure and passage forming means, said gripping means being engageable with said wedge to lock the same in desired operative position, and said wedge having a depressed portion in a face thereof bounded by keeper shoulders adapted to 120 cooperate with said gripping means when the 125

latter is loosened to thereby retain said wedge in assembled relation to said clamp bar structure.

5. A form clamping device as characterized in claim 4, in which said wedge is provided with a laterally beveled edge and said thrust abutment is provided with an undercut beveled edge to cooperate therewith.

In testimony that I claim the invention set forth above I have hereunto set my hand this 10 24th day of May, 1928.

SAMUEL S. COLT.
